DESIGN FOR AN OUTSOLE OR SIMILAR ARTICLE

George Codish, New York, N. Y.

Application December 26, 1944, Serial No. 117,091

Term of patent 14 years

(Cl. D7—5)

To all whom it may concern:

Be it known that George Codish, a citizen of United States and resident of New York city, in the county of the Bronx and State of New York, has invented a new, original, and ornamental Design for an Outsole or Similar Article, of which the following is a specification, reference being had to the accompanying drawing, forming part thereof, and in which,

Fig. 1 is a side view of the outsole, embodying my new design;

Fig. 2 is a bottom plan view; and

Fig. 3 is a cross-sectional view taken on line 3—3 of Fig. 2.

I claim:

The ornamental design for an outsole or similar article, substantially as shown.

GEORGE CODISH.
